UNITED STATES PATENT OFFICE.

JOSEPH EASTMAN, OF CHICAGO, ILLINOIS, ASSIGNOR TO THE LIGHT FIRE-PROOFING COMPANY, OF SAME PLACE.

CEILING AND FLOOR CONSTRUCTION.

SPECIFICATION forming part of Letters Patent No. 558,266, dated April 14, 1896.

Application filed October 31, 1895. Serial No. 567,514. (No model.)

To all whom it may concern:

Be it known that I, JOSEPH EASTMAN, a citizen of the United States, residing at Chicago, in the county of Cook and State of Illinois, 5 have invented a new and useful Improvement in Ceiling and Floor Construction, of which the following is a specification.

The primary object of my invention is to enable the plaster-work for the ceilings of 10 rooms in buildings to be performed by a filling-in process from the room or space above, thereby greatly expediting and cheapening the operation besides enabling, through the employment of media attached to the floor-beams for holding the plastic material, better bonding of the latter and bracing of the beams than by the old method of ceiling and floor construction, and thus affording a 15 stronger ceiling structure, the concrete or other plastic material of which, not being applied in coats or layers, will not tend to stratify under the influence of fire or frost.

Another object of my invention is to enable the floor structure above the ceiling to 20 be made or laid from the previously-formed ceiling structure, using the latter as a working platform.

I supplement the description of my invention hereinafter contained by the accompanying drawings, in which—

Figure 1 is a broken top plan view of a ceiling constructed in accordance with my improvement; Fig. 2, a broken section taken at the line 2 on Fig. 1 and viewed in the direction of the arrow; Fig. 3, a broken section taken at the line 3 on Fig. 1 and viewed in the direction of the arrow; Fig. 4, a section taken at the line 4 on Fig. 3, viewed in the direction of the arrow and enlarged; Fig. 5, 35 a section taken at the line 5 on Fig. 6 and viewed in the direction of the arrow, and Fig. 6 a broken top plan view of my preferred floor structure.

A A in Fig. 1 denote walls of a building, in 40 which are extended in suitable locations the floor-beams B, represented in the drawings as the ordinary metal I-beams, though they may be of other form or ordinary wooden floor-beams for utilization in applying my 45 improvement. At intervals of about a foot

apart, more or less, I fasten to the beams B, to extend transversely thereof across their bases, bars C, preferably of metal, and of the channelled or angle-bar variety, the form shown involving two flat parallel sides connected by a third side presenting concavo-convex surfaces to afford a better hold to the cement (mortar, concrete or the like) applied thereto in the manner hereinafter described. 55

For fastening the bars C to the floor-beams I employ suitable clips or clamps according to the forms of the floor-beams and bars. Thus for the forms thereof shown I use the clip D illustrated, comprising a piece of flat metal r, containing a T-shaped slot q, adapted 60 to be slipped, at the head portion of the T, upon a side of the bar C and to receive in its stem portion a wedge-shaped key p. This clip is applied wherever a bar C crosses a floor-beam in a manner to cause the lower 65 flange of the latter to be engaged by the key p, whereby driving the key tightens the bar in its suspended relation to the floor-beam. When the bars C have been thus placed, I string from one to the other, at suitable 70 intervals, wires w, as by winding them about the bars and stretching them from one to the other thereof, as indicated. These wires are not represented in Fig. 6, as they would tend 75 therein to confuse. After so stringing the 80 wires I erect a temporary and readily-removable ceiling E, preferably of wood, below the plane of the wires w, the ceiling being most conveniently supported on suitable horses F, and then I fill in from above upon the temporary ceiling, preferably above the level of 85 the bases of the beams B, suitable plastic material G, such as concrete, mortar, or the like. When this plastic material has set sufficiently, the temporary ceiling E may be 90 removed, leaving the permanent even ceiling afforded by the filling.

Before or after removal of the temporary ceiling I lay a floor, as a tile floor or, and preferably, a floor H of the construction hereinafter described, utilizing the preparatorily-constructed ceiling as a platform for the workmen. The floor H comprises slabs I, molded out of suitable plastic material, such as concrete, and provided to extend from floor-beam 100

to floor-beam at proper intervals, say one foot apart, and in these slabs I are preferably embedded arched metal bars I'. The slabs may be ribs, arched, as indicated by the dotted line x in Fig. 3, and they may be molded in place by placing boards the desired distance apart to extend between the floor-beams and utilizing them as molds by filling the space between them with the material of which the slabs are formed, the arched bars I' being either preliminarily placed in the molds to rest at their ends in the adjacent flanges of the I-beams B (if the floor-beams be of that variety) or forced into the plastic material before it sets. The height to which the slabs I extend should be below the tops of the floor-beams. Between the slabs I are inserted, to extend at right angles thereto and preferably about a foot apart, rectangular-shaped slabs I², formed preferably of the same plastic material as that of which the slabs I are formed, and these slabs I² may be molded in place, or they may be finished articles and be inserted into position between the slabs I. The slabs I² may, if desired, be mere bracing-ribs, fitting between the slabs or ribs I, when they would be mere oblong blocks, say about two inches square in cross-section. Over the tops of the intersecting slabs I then stretch some suitable covering, preferably wire-netting K of the kind commonly used for lathing, stapling it to the slabs and allowing it, by preference, to sag, as indicated in Fig. 5, in the spaces between the slabs, and upon this covering I apply a desired thickness of concrete or other suitable plastic material, which should extend to the upper surfaces of the floor-beams.

While I show the covering K in the drawings as extending between the beams, it is sometimes desirable, particularly if the slabs be omitted, to extend it over the beams for the sake of the additional strength thereby afforded, and it is within my invention so to extend the covering over the beams.

The construction thus described of the ceiling is expeditious and comparatively cheap and renders it particularly strong, the concrete bonding firmly together the angle-bars C, besides greatly facilitating the floor construction, and when the floor-beams are wooden my improvement dispenses with the usually employed bridging between them and avoids the necessity for "sizing" them.

What I claim as new, and desire to secure by Letters Patent, is—

1. The ceiling construction comprising, in combination with floor-beams, bars extending at intervals across the bases of the floor-beams, and fastened thereto, wires strung across the bars and a filling of concrete, or

the like, embedding said bars and wires, substantially as described.

2. The ceiling construction comprising, in combination with I-beams, angle-bars C extending at intervals across the bases of said beams, clips D connecting said angle-bars, and a filling of concrete, or the like, embedding said angle-bars, substantially as described. 65

70 3. The ceiling and floor construction comprising, in combination with the floor-beams, bars extending at intervals across the bases of the floor-beams and fastened thereto, a filling of concrete, or the like, embedding said bars, a covering K and a filling H of concrete, or the like, upon said covering, substantially as described. 75

80 4. The ceiling and floor construction comprising, in combination with the floor-beams, bars extending at intervals across the bases of the floor-beams and fastened thereto, a filling of concrete, or the like, embedding said bars, slabs I extending at intervals between the floor-beams, a covering K extending over 85 the slabs, and a filling of concrete, or the like, upon said covering, substantially as described.

90 5. The ceiling construction comprising in combination with floor-beams, bars extending at intervals across the bases of the floor-beams and fastened thereto, and a filling of concrete, or the like, embedding said bars, substantially as described.

95 6. The ceiling and floor construction comprising, in combination with the floor-beams, bars extending at intervals across the bases of the floor-beams, and fastened thereto, wires strung across the bars, a filling of concrete, or the like, embedding said bars and 100 wires, slabs I extending at intervals between the floor-beams, a covering K extending over the slabs and a filling H of concrete, or the like, upon said covering, substantially as described. 105

110 7. The ceiling and floor construction comprising, in combination with the floor-beams, bars extending at intervals across the bases of the floor-beams and fastened thereto, wires strung across the bars, a filling G of concrete or the like, embedding said bars and wires, slabs I having embedded in them the arched bars I' and extending at intervals between the floor-beams, slabs I² extending at intervals between the slabs I, a covering K extending 115 over the slabs, and a filling H of concrete, or the like, upon said covering, substantially as described.

JOSEPH EASTMAN.
